UNITED STATES PATENT OFFICE.

ARTHUR L. LEGGETT, OF DENVER, COLORADO.

SIGNALING INSTRUMENT.

Application filed March 7, 1923. Serial No. 623,434.

To all whom it may concern:

Be it known that I, ARTHUR L. LEGGETT, a citizen of the United States, residing at Denver, in the county of Denver and State 5 of Colorado, have invented certain new and useful Improvements in Signaling Instruments, of which the following is a specification.

My invention relates to signaling instruments and more particularly to electrically operated appliances of the type used on motor driven vehicles to indicate the direction of travel thereof to pedestrians and drivers of approaching or following convey- 10 ances.

It is an object of the invention to provide in a device of the above described character, an electrical operating system in which the current flow through a simple circuit controlled by means of a single switch or circuit breaker, will cause a semaphore arm or other indicatory element to be moved alternately to its operative and inoperative 15 positions.

Another object of the invention is to provide in connection with the electric circuit of the signaling appliance means which compel the indicatory element to move to and remain in either its operative or inoperative position irrespective of the length of 20 time during which the circuit is closed by actuation of the switch.

A further object resides in providing a simple and very compact arrangement of 25 the operating parts of the system, in association with means for fastening it at a side of a motor vehicle, and still other objects reside in details of construction, all of which will be fully disclosed in the following 30 description with reference to the accompanying drawings which illustrate an embodiment of the invention in commercial and practical form.

In the drawings in the several views of 35 which like parts are similarly designated.

Figure 1 represents a sectional elevation of my improved signaling instrument, showing the indicatory member thereof in its projected position;

Figure 2, a fragmentary view similar to Figure 1, showing the parts of the operating mechanism in the position they occupy when the indicatory member is in its normal inoperative position;

Figure 3, a section taken on the line 3-3, Figure 1:

Figure 4, a section along the line 4-4, Figure 1;

Figure 5, a section taken on the line 5-5, Figure 4, and Figure 6, a sectional elevation 60 looking in the direction of the arrow A in Figure 1.

Referring to the drawings, the reference numeral 2 designates a casing of suitable form and proportions, preferably made in 65 two complementary parts, which encloses the operating mechanism of the signaling element and which is provided with convenient means such as a clamp 3 for fastening it to a windshield post or other part of a 70 motor vehicle to which the invention is applied.

An insulating base 4 fastened in the casing by means of screws 5 supports the coil 6 of a solenoid, and in axial relation thereto, a hollow column 7 which supports a horizontally disposed solenoid 8 of smaller proportions.

The coil of the last mentioned solenoid is fastened upon the column 7 by means of 80 a strap 9 which has an upwardly extending arm 10 for its rigid connection at the top of the casing. Fastened to the casing at opposite sides of the column, are two plates 12 of non-conducting material which are 85 members of a frame which supports the signaling element and the parts of the electric controlling mechanism of the same.

The signaling element consists in the form of the invention shown in the drawings, of a semaphore arm 13 which is pivoted between the members of the frame by means of a shaft 14. The arm is preferably hollow and provided in its sides with openings 15 shaped in the form of an outwardly 95 pointing arrow and covered by panes of glass, mica or other transparent material.

An incandescent lamp 16 in the arm illuminates the coverings of its openings to render the signal discernible at night, and 100 this lamp is automatically connected in the circuit when the arm is placed in its projecting position as will hereinafter be more fully described.

The inner extremity of the arm at which 105 it is pivoted on the supporting frame, consists of a plate 17 provided with a toothed segment 18 which meshes with a rack 19 on the core 20 of the solenoid 6, which slides in the hollow column 7 as best shown 110 in Figures 4 and 5.

The plate has furthermore a peripheral

notch 21 which is engaged by a gravity-latch 22 to lock the arm in its operative position. The latch is pivoted on the frame as at 23, and it has a slot for its connection 5 with a head on the sliding core 24 of the horizontally disposed solenoid 8.

A coiled spring 25 in the hollow of the solenoid coil acts upon the sliding core to yieldingly maintain it in its projected position, and its head is sufficiently narrow with 10 relation to the slot of the latch in which it extends, to permit of a limited independent movement of the core when it is drawn inwardly by the magnetic force upon energization of the solenoid.

Mounted upon the shaft 14 of the signaling arm is a cam 26 which engages with a resilient arm 27 of an automatic switch which constitutes a distinctive and valuable 20 feature of the invention. The switch comprises in connection with the arm 27, an insulated finger 28 which co-operates with insulated contact-pins 29 and 30 on the frame to alternately energize the two solenoids as will hereinafter be explained.

The arm 27 and the finger 28 are fastened upon a block 31 of non-conductive material which is secured at the end of a pivot pin 32 supported in aligned openings of the members 12 of the supporting frame, and the shaft carries between said members, a bar 33 which in the operation of the device, serves to prevent the automatic switch from reversing its position until after the circuit 35 of the instrument is reopened in the main controlling switch.

The bar carries at its extremities soft iron armatures 34 and 35 disposed to engage respectively with a pole piece 36 at the end of 40 the solenoid 8 and with an exposed side of the vertically sliding core 7 of the solenoid 6, and the last mentioned solenoid has a soft iron shell 37 provided with a pole piece 38 for the magnetic induction of the respective 45 armature.

A flat spring 39 bears upon the resilient arm 27 of the automatic switch to yieldingly maintain it in engagement with the cam.

The electric circuit of the instrument diagrammatically illustrated in the drawings, 50 comprises in association with a source of electricity 40, a conductor 41 connecting a pole of the source with the contact finger 28 of the automatic switch, conductors 42 and 55 43 which connect the contacts 30 and 29 respectively with the coils of the solenoids 8 and 6, ground connections 44 and 45 at the opposite ends of the coils, and a ground connection 46 at the opposite pole of the source 60 of electricity.

A switch 47, preferably of the push-button type, controls the flow of current through the circuit and is in practice fastened either on the dash board or the steering wheel of the vehicle or at any other 65

place where it is within convenient reach of the driver.

The lamp on the semaphore arm is connected in the circuit when the arm is in its signaling position, through the medium of 70 an automatic switch consisting of a contact blade 48 fastened at one end upon the supporting frame, a contact 49 on the plate of the signaling arm with which the blade engages when the arm is in its projecting position, and a segment 50 of non-conductive material upon which the blade rides during movement of the arm to its retracted position.

The terminals of the incandescent lamp 80 connect respectively with the contact 49 by means of a conductor 51 and with the ground as at 52, and the blade 48 is electrically connected with the source of electricity through the medium of a conductor 53.

When the device is applied to a motor driven vehicle of the internal combustion or explosion type, the battery of the ignition and lighting systems of the vehicle, provides a convenient medium for the operation of 90 the signaling arm and the electrical connections between the parts of the mechanism of the direction indicator and the battery as hereinbefore described, may be made through the medium of conveniently located conductors of the lighting or ignition systems if so desired.

As stated hereinbefore, my invention is particularly adapted for use as a direction indicator for motor vehicles and as such, it 100 is preferably fastened at the driver's side of the vehicle either at the front or at the rear end of the frame, or two or more of the appliances electrically interconnected for synchronous operation, may be applied 105 at opposite sides of the vehicle, or at both the front and the rear end of the same as may be desired.

It will be apparent, however, that the invention may be advantageously employed 110 for other purposes, as for example, in signaling systems of railways, and that in the place of a pivoted signal arm, any visual or audible signal may be employed within the spirit of my invention.

It should furthermore be understood that while the operating mechanism as shown and hereinabove described, is particularly adapted for use in signaling devices, it may be effectively employed wherever it is desired to move an actuated element alternately from one determinate position to another through the medium of a simple circuit controlled by a single switch.

In the operation of the signaling instrument, the arm 13 normally occupies the inoperative position illustrated in Figure 2, in which the main switch 47 is open and the contact finger 28 of the automatic switch engages with the contact 29 of the solenoid 6.

The blade 48 of the lamp-switch rests in this position of the arm, upon the insulating segment 50.

Now, if it is desired to move the signal-arm to its operative or projecting position, the operator closes the switch 47 and thereby energizes the solenoid 6 by a flow of current along a course which includes beginning at the source of electricity, the conductor 41, the contact finger 28 of the automatic switch, the conductor 43 connecting the contact 29 with the coil of the solenoid 6, and the ground.

The magnetic force produced in the solenoid, draws its core inwardly and through the instrumentality of the rack and segment causes the semaphore arm to move upwardly about its pivotal axis until the gravity latch influenced by the spring pressing upon the sliding core of the solenoid 8, enters the notch in the edge of the plate 17 and thereby locks the arm in its projected position.

The armature 35 on the bar 33 of the automatic switch will freeze to the core of the solenoid 6 as long as the current flow is continued so that even though the operator holds the switch in the closed position beyond the period required to move the arm to its projected position, the arm will remain in said position and can not be returned to its normal position until after the switch has been released.

During the upward movement of the arm 13, the cam 26 lifts the resilient arm 27 of the automatic switch in order to reverse the position of the finger 28, but the finger is prevented from following the movement of the arm until after the circuit has been reopened in the switch 47 and the bar 33 is in consequence released, when by the resilience of the arm 27 the finger 28 is compelled to move into engagement with the contact 30 as shown in Figure 1.

When subsequently the circuit is again completed by means of the switch 47, the solenoid 8 is energized and the magnetic force produced in the solenoid causes its core to be drawn inwardly against the resistance of the spring 25 with the result that the catch 50 is disengaged from the notch in the peripheral edge of the plate of the signal arm and the latter is released to move by gravity to its original inoperative position.

The downward movement of the arm again tends to reverse the position of the automatic switch and the magnetic force in the solenoid will cause the armature 34 at the upper end of the bar 33 to freeze to the metal plate 36 at the end of the solenoid 6 and thereby prevent the reversal of the switch until after the circuit has been reopened.

It will be understood that owing to the resiliency of the arm of the switch, the cam 65 can under the above circumstances complete

its movement with the arm without effecting the movement of the switch until after the circuit has been broken in the switch 47.

The lamp in the semaphore arm is in the operation, lighted when the arm is in its signaling position and extinguished while it moves to its inoperative position through the instrumentality of the switch composed of the moving contact 49 and the relatively stationary blade 48.

Having thus described my invention it will be evident that by completion of a simple circuit through the medium of a single switch the signaling element may be placed in either its operative or inoperative position irrespective of the period during which the circuit is closed, and that for that reason as well as owing to the simplicity and compactness of its construction, the appliance is particularly adapted for use on motor driven vehicles to indicate the direction of travel thereof.

It will be understood that the mechanism as shown in the drawings, is subject to variations in the construction and arrangement of its parts and that such variations may be resorted to within the spirit of the invention as defined in the hereunto appended claims.

What I claim and desire to secure by Letters Patent is:

1. In an electro-mechanical movement, the combination with an element adapted to move alternately from one to another of two determinate positions, of an electro-magnetic device to move the element to one of said positions, a latch to hold the element in said position, an electro-magnetic device acting upon the latch, to cause the element to return to the other position, a circuit for said devices, a switch in said circuit, and an automatic switch adapted to connect said devices alternately in the circuit by movement of said element, and including means controlled by the current flow through said devices to hold the automatic switch from operating until after the circuit has been reopened in the first mentioned switch.

2. A signaling instrument comprising a signal-element mounted to move from a normal inoperative position to a determinate operative position, an electro-magnetic device adapted to effect said movement of the element, a latch adapted to lock the element in its operative position, a second electro-magnetic device adapted to release the element by action upon the latch, a circuit for said devices, a switch controlling the circuit, and an automatic switch adapted to connect said devices alternately in the circuit by movement of the signal-element and including means controlled by the current flow through the electro-magnets to hold it from operating until after the circuit has been reopened in the first mentioned switch.

3. A signaling instrument comprising a

pivoted signal arm having a toothed segment, an electro-magnet including a movable member having a rack meshing with the segment, a latch for locking the arm in an operative position to which it has been moved by the action of the electro-magnet, a second electro-magnet acting upon the latch to release the arm, a circuit for the electro-magnets, a switch controlling the circuit, and 10 an automatic switch adapted to connect the electro-magnets alternately in the circuit by movement of the arm, and including a magnetically influenced member which by the current flow through the electro-magnets, 15 holds the automatic switch upon each completion of the circuit until after the circuit is re-opened in the first mentioned switch.

4. A signaling instrument comprising a pivoted signal arm, a cam mounted to move with the arm, an electro-magnetic device for moving the arm to a determinate operative position, a latch for locking the arm in said position, an electro-magnetic device acting upon the latch to release the arm, a circuit for the electro-magnets, a switch controlling the circuit, and an automatic switch including contacts in electrical connection with the electro-magnets, a contact member connected in the circuit and movable to alternately engage said contacts, a yieldable member adapted to effect said movements of the contact member by rotation of the cam, and a magnetically influenced member which by the current flow through the electro-magnets holds the automatic switch upon each completion of the circuit until after the circuit is reopened in the first mentioned switch.

5. A signaling instrument comprising a signal element mounted to move from a normal inoperative position to a determinate operative position, an electro-magnetic device adapted to effect said movement of the element, a latch adapted to lock the element in its operative position, a second electro-magnetic device adapted to release the element by action upon the latch, a circuit for said devices, a switch controlling the circuit, and an automatic switch adapted to con-

nect said devices alternately in the circuit by movement of the signal-element and including an oscillating bar and armatures thereon disposed to freeze to the respective electro-magnets and thereby hold the automatic switch from operation at each completion of the circuit until after the circuit is reopened in the first mentioned switch.

6. A signaling instrument comprising a movable signal element, an electro-magnetic device for moving the element to a determinate operative position, a latch to lock the element in said position, a second electro-magnetic device acting upon the latch to release the element, a circuit for the electro-magnets, a switch in the circuit, and an automatic switch including two contacts electrically connected respectively with the electro-magnets, an oscillating contact member connected in the circuit and adapted to engage alternately with said contacts, a yieldable member to effect the movement of the contact member by the movements of the signal element, and a locking member controlling the movements of the contact member and having armatures co-operative with the electro-magnets to hold the contact-member at each completion of the circuit until after the circuit is reopened in the first mentioned switch.

7. A signaling instrument comprising a signal element, an electro-magnetic device adapted to place said element in an operative condition, a second electro-magnetic device for maintaining the element in said condition, a circuit for the electro-magnets, a switch controlling the circuit, and an automatic switch adapted to alternately connect the electro-magnets in the circuit by the operation of the instrument and including means controlled by the current flow through the electro-magnets to prevent the operation of the automatic switch at each completion of the circuit until after the circuit is reopened in the first mentioned switch.

In testimony whereof I have affixed my signature.

ARTHUR L. LEGGETT.
